UNITED STATES PATENT OFFICE.

JANE L. W. MURRAY, OF CRAIGLOCKHART, SCOTLAND.

PIECE OF FURNITURE CONVERTIBLE FOR USE AS A BED, COUCH, BATH-CHAIR, OR THE LIKE.

1,271,515.

Specification of Letters Patent.

Patented July 2, 1918.

Application filed March 2, 1917. Serial No. 152,030.

To all whom it may concern:

Be it known that I, JANE LOUDON WALKER MURRAY, a subject of the King of Great Britain and Ireland, and a resident 5 of Craiglockhart, in the county of Midlothian, Scotland, have invented a new and useful Piece of Furniture Convertible for use as a Bed, Couch, Bath-Chair, or the like of which the following is the specification.

10 The invention relates to furniture of the type which is convertible for use as a bed, a couch, a carrying chair or the like, or one or more of them, and which has a central or seat member, a head member pivoted to one 15 end thereof, and a leg member pivoted to the other end, the leg member having in some cases a foot member hinged in turn to it, the head and leg members being so articulated together that on the head member 20 being either raised or lowered the position of the leg member is also adjusted; and the invention has for its object to provide an improved piece of furniture of this type capable of use also as a bath chair or a 25 stretcher, and simple in construction considering its various capacities, of light weight, and easily operable.

An illustrative but not limitative example 30 of the piece of furniture is shown on four accompanying sheets of explanatory drawings. In these drawings Figure 1 and Fig. 2 are respectively a plan and a side elevation, with certain parts omitted to avoid confusion, of the structure as a bed, and 35 Fig. 3 is a side elevation showing the structure arranged as a bath chair, while Figs. 4 and 5 are respectively a plan and a side elevation of details hereinafter referred to, the last mentioned figure being drawn to an 40 enlarged scale.

Fig. 6 is a perspective showing the rectangular shape of the frames J and J²;

Fig. 7 is a perspective of a book rest or support E, E¹, E².

45 As shown in the drawings there is provided a central braced structure A provided with supporting posts A¹ and forming approximately the central part of the bed and the seat of the bath chair when the apparatus is so used. To one end of this central structure is pivoted what may be termed a head member or frame A³, consisting of two rods or tubes pivoted at A⁴ on the opposite sides of the central structure A and connected together at their upper ends by a

transverse part. To the other end of the central structure A there are pivoted straps A⁵ (Fig. 3) securing and forming a hinge for a second structure constituting an intermediate or leg member B. To the forward end of this leg member is pivoted a foot member B¹. The rods forming the sides of the main head member A³ are extended below the pivots A⁴ and pivoted to the rods A⁶ which extend to and are rigidly 60 connected with the foot member B¹. There is also provided a subsidiary head member B² pivoted on the same axis as the main head member A³ and forming in certain positions of the structure a back rest. The central 65 structure A, the subsidiary head member B² the leg member B and the foot member B¹ are all shown as fitted with ordinary metal lath mattresses B³ for the sake of clearness in drawing, though of course spring or other 70 convenient form of mattresses may be employed, and these are upholstered in any 75 convenient manner. On each side of the subsidiary head member B² is a wormwheel quadrant C (Fig. 5) gearing with a worm 80 C¹ on a spindle C² turning in bearings in a bracket C³ on the central structure A. These spindles C² have on them bevel pinions C⁴ each of which gears with a similar bevel pinion C⁵ on the opposite ends of a 85 transverse shaft C⁶ which may be fitted with a handle or with a handwheel, (not shown) easily accessible to the occupant. The subsidiary head member B² has on it catches D 90 by means of which it may be locked to the main head member A³. When these catches are free and the parts in the bed position, on operation of the gearing the subsidiary head member B² alone may be adjusted to any 95 desired angle and thus form a bed back rest. When however the subsidiary head member B² is locked by the catches D to the main head member A³, on operating the gearing these two members are raised together and, as the main head member A³, the leg member B and the foot member B¹ are articulated to one another as hereinbefore described, upon the head member A³ being 100 raised into an angled position the leg member B is lowered accordingly, and the foot member B¹ substantially maintaining its horizontal position finally becomes the foot rest of a bath chair. The worms C¹ and wormwheels C in the operating gearing are 105 of such pitch that the various members of 110

the structure are securely held in any position to which they are adjusted. The chain lines in Fig. 2 show the parts in the position they would assume when adjusted to practically midway between the bed and bath chair positions, in which position they form what may be termed an inclined couch. The leg member B has parts extending beyond its point of pivoting A⁵ to the central structure A toward the head member A³, and these parts are connected by links D¹ to the head member. These links form arms in the bath chair position and also serve to secure the parts rigidly in their various positions. Along the sides of the various members are arranged flaps D² which may be turned horizontally as shown in Fig. 1 to increase the effective width of the bed, or they may be turned up as shown in Fig. 3 to protect and inclose the occupant when the apparatus is in use as a bath chair. Means such as thumb screws similar to J³, Fig. 2, but for the sake of clearness, not shown, are provided for locking the flaps D² in any desired position. The foot member B¹ carries at opposite sides upstanding slotted tubes D³ braced together to form the foot of the bed, and rods D⁴ carrying pawls D⁵ slide in these tubes so that they may be lowered to support that member when the apparatus is in use as a bed, or raised when that member becomes the foot-rest of a bath chair. The pawls D⁵ engage catches on the tubes D³ and hold the rods D⁴ in either position. To the subsidiary head member B² is attached a device forming a book rest and table support. This device is only shown in Fig. 3 by chain lines for the sake of clearness in drawing, and it consists of two rods E hinged at one end to the opposite sides of the subsidiary head member and having hinged to their opposite ends two other rods E¹ to which in turn is hinged a U-shaped rod E² forming in the position shown the tray support or book rest. When not in use the supporting rod E² is turned up against the rods E¹ and the whole turned over so that it extends down the back of the subsidiary head member B². At the head end of the structure there is also a frame, the side members G of which run on guides G¹ (Fig. 5) on the central structure A. A rack is formed on each side member with which there gears a pinion G² on a transverse shaft G³ the ends of which are squared to receive a handle so that the frame may be moved outward or inward. This frame has posts H bearing upon the floor and adapted to support the apparatus when it is in bed-form. These posts H extend upward and carry at their upper ends arms H¹ pivoted to swing horizontally, adapted to carry curtains or the like, and so interconnected, as shown in Fig. 4, by a link H² that movement of one causes move-

ment of the other in the opposite direction. The posts H also carry a hood and screen device when the apparatus is in use as a bath chair. This device consists of a rectangular frame J pivoted to the upper ends of the posts and supported at its outer side by stays J¹. To this frame there is hinged a second like frame J² both capable of being locked in any desired position by thumb screws J³, J⁴ (Fig. 2). They are covered with any suitable material, and the covering of the second frame J² may be provided with an aperture glazed with, for example, celluloid. When desired the second frame J² may be folded back on to the first frame J or on loosening the thumb screws J³, J⁴, the frame J may be turned up into the vertical position, the lower end of the stays J¹ then sliding on the rod H and the frame J² be made to lie horizontally as shown by dotted lines in Fig. 2, or the latter frame may be folded over so as to extend down the back of the structure.

A wheeled under-carriage K is provided, this carriage being so shaped and pivoted at its rear upon the supporting posts A¹ of the central structure A that, when the apparatus is in use as a bed, only the rear wheels touch the ground, but when the apparatus is to be used as a chair and the foot member B¹ is being brought down as hereinbefore described, cam-like arms K¹ thereon engage the front end of the carriage so that its front wheels are forced into contact with the floor. This movement of the parts also raises the central structure A off the ground into the position shown in Fig. 3. Handles L telescoping within tubes L¹ are provided at head and foot so that the apparatus may be used as a litter or carrying chair.

What I claim is:—

1. A piece of furniture of the type described comprising a central structure, a main head member pivoted to one end thereof, a subsidiary head member also pivoted to said central structure, means for adjusting the position of said subsidiary member independently of the main head member, and means for securing said head members together at will to cause the main head member to follow the subsidiary head member on the operation of said adjusting means for the latter.

2. In combination with a construction such as that recited in claim 1, a leg member pivoted to the other end of the central structure, and an operative connection between the main head member and the leg member to effect the joint movement thereof on the operation of the adjusting mechanism for the subsidiary head member when the latter is attached to the main head member.

3. In combination with a construction such as that recited in claim 2, a foot mem-

- ber at the lower end of the leg member and rigid with the connecting member which extends between the main head member and the leg member.
- 5 4. A piece of furniture of the type described comprising a central structure, a main head member pivoted to one end thereof, a subsidiary head member also pivoted to said central structure, and on each side of 10 said subsidiary member a worm wheel quadrant, a worm meshing therewith, a bevel gear for operating said worm, in combination with a transverse shaft having at each end a second bevel gear meshing with said 15 first-mentioned bevel gear, and means for rotating said transverse shaft to raise or lower said subsidiary member, together with means for securing together at will said main and subsidiary head members whereby 20 they may be adjusted in unison or the subsidiary member alone, substantially as described.
5. A piece of furniture of the type described having a central structure, a head member pivoted to one end of said central structure, an intermediate or leg member pivoted to the other end thereof, and a foot member pivoted in turn to the leg member, in combination with a wheeled under carriage, the frame of which is rigid and pivoted at its rear upon the central structure, and cam-like arms on the foot member engaging the front end of the carriage when the foot member descends, so that the front wheels of the carriage are forced into contact with the floor and the central structure raised, substantially as described. 25 30 35

In testimony whereof I have signed my name to this specification, in the presence of two subscribing witnesses.
